UNITED STATES PATENT OFFICE

LEONARD S. COPELIN, OF COMPTON, CALIFORNIA

RECIPROCATING CORE DRILL

Application filed November 29, 1926. Serial No. 151,399.

My invention relates to core drills of the type which reciprocates during the coring operation, being particularly designed for attachment to the ordinary cable used in the 5 standard type of well drilling.

Generally, my core drill consists of an outer barrel attached, through proper attaching members, to the cable in such a manner as to permit rotative movement of 10 the outer barrel as may be imparted to such outer barrel by the twist of the cable. Within the outer barrel is mounted an inner barrel or core tube which has a limited longitudinal movement therein and at the same 15 time so mounted that the rotative movement of the outer barrel is not imparted to the inner barrel.

The principal object of my invention is to provide a core drill of the type described 20 which is so constructed that the core, while being formed is protected against undue jarring action and strain which would otherwise have a tendency to injure the core.

Another object of my invention is to provide a core drill of the class described having 25 its parts so arranged that the fluid between the barrels is prevented from jetting against the core but directed outwardly over the outer cutting teeth, thereby assisting in 30 cleaning the cuttings and other accumulations from the teeth.

Other advantages and objects will appear to those skilled in the art from the following description and drawings.

35 Referring to the drawings, which are for illustrative purposes only,

Fig. 1 is a vertical sectional view of a drill embodying a form of my invention.

Fig. 2 is an enlarged sectional plan view, 40 taken on the line 2-2 of Fig. 1.

Fig. 3 is an enlarged inverted plan view of the lower or cutting end of the drill.

My core drill in the form shown consists of an outer barrel 11 threaded to a body 45 member 12, such body member terminating at its upper end in a threaded pin 13 suitable for connection to an ordinary string of cable tools, the drill and cable tools (not shown) being suspended in the hole by 50 means of the ordinary cable, (not shown).

The lower end of the outer barrel 11 is provided with a circular cutting member or shoe 15, which is interiorly shouldered as indicated at 16 for purposes hereinafter described, such cutting member 15 also being provided with a central opening 17, in the face of which are disposed a series of vertically extending grooves 18 to permit of movement of fluid or mud between the inner and outer barrels of the drill. 55

Freely rotatable in the outer barrel 12 is an inner barrel 20, terminating at its lower end in a circular cutter 21 threaded thereto, a core catcher consisting of a ring 22 having fingers 23 mounted thereon being supported 60 between the lower end of the barrel 20 and a shoulder 24 formed on the face of the cutter 21. The inner cutter 21 is formed with a series of teeth indicated at 25 and the outer cutting member 15 is formed with 65 a series of radially extending teeth 26, the teeth 26 having radially extending passages 27 therebetween to permit free movement of cuttings and fluid or mud under the cutting member 15. It is to be understood however, that the teeth of the respective inner and outer cutters may be varied 70 in form without departing from the spirit and scope of my invention. 75

The upper end of the inner barrel 20 is 80 provided with a head 28 threaded thereto, the head being of larger diameter than the inner barrel and being provided with a series of vertically extending passages 29 for the purposes hereinafter referred to. 85 The head 28 is provided with a vertically extending central passage 30 fitted with a relief valve 31, such valve being arranged to permit fluid or other material in the inner barrel above the core to pass upwardly 90 therethrough during the coring operation, such valve being closed at the end of the coring operation, also assisting in creating a vacuum above the core should the core start to slide out of the core barrel, thereby 95 assisting to retain the core in the barrel during the operation of removing the drill from the hole. The head 28 is also provided with a nipple 32 extending upwardly therefrom, such nipple extending through a cen- 100

tral opening or passage 33 in a plug 34 and engaging when in its upper position with a ball bearing organization 35 elastically held downwardly by means of a coil spring 36 mounted in a chamber 37, in the body member 12, the fluid or mud in the core barrel heretofore referred to being permitted to pass upwardly through the valve 31, the nipple 32 and out through passages 38 and 39 in the head 12.

10 The drill is operated in the following manner: The drill supported on the lower end of the cable as heretofore described is alternately raised and dropped in the well, 15 being dropped to allow the cutting shoe to strike a blow on the formation and having a spinning or rotative movement imparted thereto by the twist in the cable.

16 The inner barrel or core tube, being free 20 to move in the outer barrel, engages the formation before the outer cutter strikes the same and as the outer barrel moves downwardly over the inner barrel, the nipple 32 engages bearing 35 and is yieldingly 25 pressed downward, so that the cutter on the inner barrel is yieldingly held against the formation, as the outer cutter strikes the formation, further movement of the outer barrel causes the plug 34 to strike the head 30 28, thereby imparting a blow to the inner barrel.

35 During this movement just described, it will be noted that the nipple 32 enters the opening or passage 33 in the plug 34 and 40 shuts off passage of the mud from between the two barrels upward. The downward movement of the outer barrel displacing the mud above the head 28 through the grooves or slots 29 in the head causing the mud to be forcibly expelled through the slots 18 in 45 the shoe outwardly therefrom, around the teeth on the shoe 15, the core being protected during this movement from the mud due to the fact that the inner barrel is yieldingly held against the formation until it receives a blow as above described.

50 The spring 36, also momentarily holds the inner barrel and cutter thereon against the formation as the outer barrel starts on its upward movement, thereby protecting the core from the consequent agitation of the mud in the bottom of the hole.

55 As the core forms, it passes upwardly in the inner or core barrel, being caught by the fingers 23, the mud or fluid in the barrel above the core passing out of the core barrel through valve 31.

60 While I have shown and described the preferred form of my invention, it is to be understood that those skilled in the art may modify the construction shown without departing from the spirit of my invention.

I claim as my invention:

65 1. A reciprocating core drill comprising: an outer barrel; an inner barrel freely mov-

able therein and spaced apart from the outer barrel; cutters on the lower end of each barrel; means for yieldingly holding the inner barrel on the formation during the cutting operation, and means for forcing a quantity 70 of the mud from between the barrels outwardly, under the cutters on the outer barrel, just prior to the engagement of the cutters on the outer barrel with the formation.

75 2. A reciprocating core drill comprising a body member having mud passage therethrough; an outer barrel mounted on said body member, an inner barrel freely mounted in said outer barrel and spaced apart from the outer barrel, cutters on the lower ends of each barrel, and means on the inner barrel adapted to enter the mud passage in said body member during a portion 80 of the stroke to prevent the passage of mud from between the barrels through the mud passage in said body member.

85 3. A reciprocating core drill comprising a body member adapted to be attached to a cable, a chamber in said body member communicating with mud passages thereinabove, resilient means in said chamber, a closed outer barrel on said body member, an inner barrel freely mounted in said outer barrel spaced apart therefrom, cutters on the lower 90 end of both barrels, and means on said inner barrel arranged to move upwardly into said chamber and engage said resilient means therein.

95 4. A reciprocating core drill comprising a body member adapted to be attached to a cable, a chamber in said body member communicating with mud passages therein, resilient means in said chamber, a plug for said chamber having a passage therein,—an outer barrel on said body member, an inner barrel freely mounted in said outer barrel spaced apart therefrom, cutters on the lower end of both barrels,—a head on the inner barrel having a passage therethrough, a valve in said passage, and a hollow nipple on said head adapted to enter and close the passage in said plug and engage the resilient means in said chamber.

100 In testimony whereof, I have hereunto set my hand at Los Angeles, California, this 22nd day of November, 1926.

LEONARD S. COPELIN.
